UNITED STATES PATENT OFFICE.

FERDINAND E. LIBENOW, OF SPOKANE, WASHINGTON, ASSIGNOR OF TWO-THIRDS TO DANIEL J. MUNN, OF NEW WESTMINSTER, CANADA.

DESIGN FOR A BADGE.

SPECIFICATION forming part of Design No. 33,183, dated September 11, 1900.

Application filed July 31, 1900. Serial No. 26,468. Term of patent 7 years.

To all whom it may concern:

Be it known that I, FERDINAND E. LIBENOW, residing at Spokane, in the county of Spokane and State of Washington, have invented and produced a new and original Design for Badges, of which the following is a specification, reference being had to the accompanying drawings, which form a part thereof, in which—

Figure 1 is a front view of my design for a badge. Fig. 2 is a vertical section on the line 2 2 of Fig. 1, and Fig. 3 is a similar view on the line 3 3 of Fig. 1.

My design consists, essentially, of a body portion 1 and surrounding ornamentalations, (indicated generally by 2,) the body portion in face view comprising a lower part 1^a, having the appearance of a bucket or pail, and the upper end of the said body, at diametrically opposite sides, terminates in ears 1^b, with which the bail-like member 3 joins. The bail 3 extends vertically and has a handle 4, disposed centrally between two side ornamentalations 2^a 2^b. The upper end of the body portion 1^a also has a dome-like top 5, the crown of which extends vertically upward and has the shape of an inverted tin cup, as indicated by 6, said cup-like portion having a laterally-extending handle 6^a. The body member 1^a

has a series of cut-out portions arbitrarily arranged and of suitable ornamental configurations, said openings being indicated by 7, and the cup end also has similar ornamental openings, (indicated by 8.)

The body part of my badge as viewed from the front is a contour of a workingman's dinner-pail with ornamental openings in the bottom and top portions thereof, as hereinbefore stated, and shown in the drawings, the same appearing as seated between the two side ornamentalations 2^a 2^b, each of which is in the nature of a flag, the staffs of which are extended upwardly divergently from the body 1, the banner portions of the flags folding over toward the sides of the body portion 1. In horizontal section the body portion 1 of the body has a convex shape, as best shown in Fig. 3.

Having thus described my invention, what I claim, and desire to secure by Letters Patent, is—

The design for a badge, substantially as herein shown and described.

FERDINAND E. LIBENOW.
